UNITED STATES PATENT OFFICE.

JOHN M. GRIER, OF SALT LAKE CITY, UTAH.

ORNAMENTAL-CEILING-SETTING APPARATUS.

1,314,325.

Specification of Letters Patent. Patented Aug. 26, 1919.

Application filed January 23, 1918. Serial No. 213,426.

To all whom it may concern:

Be it known that I, JOHN M. GRIER, a citizen of the United States, residing at Salt Lake City, in the county of Salt Lake and State of Utah, have invented certain new and useful Improvements in Ornamental-Ceiling-Setting Apparatus, of which the following is a specification.

My invention relates to apparatuses for placing and setting ornamental ceilings, and has for its object to provide an efficient apparatus upon which may be placed sections or ornamental coffer panel ceilings and then to raise said panels and hold them in place until they are set and secured to form a ceiling.

These objects I accomplish with the apparatus illustrated in the accompanying drawings in which similar letters and numerals of reference indicate like parts throughout the several figures and as described in the specification forming a part of this application and pointed out in the appended claims.

In the drawings in which I have shown a substantial embodiment of my invention Figure 1 is an elevation of my apparatus shown in position in the corner of a room and with a section of a coffer panel thereon ready to be raised, held and secured in place in the corner of the room contiguous the cornice, parts cut away. Fig. 2 is an elevation of the apparatus with the same section raised and secured in place, parts cut away. Fig. 3 is an end view of the apparatus with a section of the ceiling panel thereon ready to be raised into position. Fig. 4 is a fragment of a ceiling after the same has been set in place with my apparatus. Fig. 5 is an end elevation of the detachable rack, and Fig. 6 is an end view of the platform operable in the rack with portions of the ropes cut away. Fig. 7 is a side elevation of the platform showing a modification for curved table or top used when an arched ceiling is required, and with the knock-down features shown in dotted lines.

It is often found difficult to handle, hold and secure coffer panels of a ceiling, on account of weight and the rigidity with which they must be held in place while the setting takes place. The workmen must frequently walk around on scaffolding under the panels and on which the panels are secured thereby breaking the plastic cement while the chemical changes are taking place.

in the cement, and I have invented an apparatus consisting of a scaffolding, a rack mounted thereon which may be knocked down, and an adjustable platform operable in said rack upon which the ornamental coffer panels for a ceiling may be placed, raised into position and held rigidly in place while the workmen fasten the sections of the ceiling to the suspended frame work.

The scaffolding consists of a top or floor A supported by braces B upon which the rack C is mounted. The said rack is made of pieces detachably fastened together by bolts and nuts and consists of the cross beams 1 and 2 and the posts 3 upon which are provided tenons to fit in mortises cut in the said beams 1 and 2. Angled braces 4 set into the posts 3 and beams 1, with the longitudinal ties 5 and angled braces 6 constitute the rack. The platform D is provided to operate within the rack C, and consists of the uprights 7, one at each corner, to which are bolted the cross pieces 8, one at each end, and side pieces 9, one for each side, with angled braces 10, and the top or table 11. This may be flat as shown in Figs. 1, 2, 3, 5 and 6 or curved as shown in Fig. 7 at 12. Blocks 13 are fastened to the cross beam 2, and similar blocks 14 are secured to the cross beam 8 which blocks with the ropes 15 form the blocks and tackles by which the platform D is raised and lowered in the said rack C. A free space is provided on all sides between the said platform D and the rack C. I use ropes for the tackles instead of wire cables for the reason that ropes are more flexible, and it is necessary that the means used to hold the said platform D in what might well be called the setting position, must not yield longitudinally but be free to move laterally, in order that when the panels are raised and held in position for setting on the ceiling, the workmen may walk around on the scaffold A without their actions, movements or weight imparting any shock or movement to the panel.

The operation of my apparatus is as follows:—

The scaffold is erected in the room with the floor thereof at practically seven feet below the frame work to which the ceiling panels are to be fastened, this frame work usually consists of light channel or angle irons *a* crossing at right angles and suspended from the concrete slabs or joists *b* of the room, by short rods *c*. The rack C

is assembled by placing the tenons of the post 3 in the mortises of the beams 1 and 2, and with the braces 4 in position. The sides of the rack are then bolted in place after 5 the platform D has been assembled within the rack. The rack and platform are both so constructed that they may be easily knocked down, as it is frequently necessary to move around or under ceiling beams. 10 With the cornice e run in place on the metal furring d, the coffer panels which have been previously prepared, are placed on the platform. The blocks and tackles are mounted on the cross pieces 8 of the platform D and 15 the beams 2 of the rack C. When the ropes 15 are pulled longitudinally over the blocks 13 and 14, the platform D and coffer panel thereon will be raised and may be held in position by fastening the said ropes, while 20 the workmen secure the panel in place. The securing or fastening of the section of the panels is by using long fibered material such as waste, hemp and rope pieces, which has been dipped and saturated in casting plaster, 25 a plastic cement used for such purposes and looping it over the said frame work and cementing the ends of said fiber to the back or upper side of said panels. When the 30 said casting plaster has set the panels will be firmly held in place, and the platform D and rack C may be moved and used in setting the next panel. The use of ropes 15 on the blocks 13 and 14 to raise and lower the 35 said platform D and hold it in the raised position, and the free space between the said platform D and rack C will allow the workmen to walk around on the scaffold without in any way moving the platform or in any unintentional way imparting a shock 40 or movement to the panel while the said casting plaster is setting yet leave the panel

free before the casting plaster has set so that the workmen may move it laterally and make the matched joints required.

The essential features of my invention are 45 the knock down rack, the platform operable therein and movable vertically and laterally and the manner and means of raising, holding and lowering it, and the use of ropes for operating said platform. 50

Having thus described my invention I desire to secure by Letters Patent and claim:—

1. In an apparatus of the class described the combination with a scaffold; of a rack mounted thereon having detachable sides 55 and ends; a platform operable within said rack and spaced on all sides from the frames composing said rack; and blocks and tackle on each end of said platform and rack to raise and lower said platform within said 60 rack.

2. In an apparatus of the class described the combination with a scaffold; of a rack mounted thereon; a platform having less dimensions than said rack to provide a free 65 space between the relatively movable walls of the rack and said platform; and blocks and ropes operable thereon to raise and lower said platform within said rack and retain it in position free at all times from 70 contact with said rack.

3. A coffer panel setting apparatus comprising a scaffold; a rack to be mounted on said scaffold; a platform of less dimensions than said rack operable therein with a free 75 space between its outer dimensions and the inner dimension of said rack; and means to raise and lower said platform within said rack.

In testimony whereof I have affixed my 80 signature.

JOHN M. GRIER.

Copies of this patent may be obtained for five cents each, by addressing the "Commissioner of Patents, Washington, D. C."
